UNITED STATES PATENT OFFICE.

FRED A. PUTNAM AND PERCY I. ALEXANDER, OF MELROSE, MASSACHUSETTS, ASSIGNEES
TO MARKEM MACHINE COMPANY, OF BOSTON, MASSACHUSETTS, A CORPORATION OF
MASSACHUSETTS.

MARKING-MACHINE.

1,261,163.

Specification of Letters Patent.

Patented Apr. 2, 1918.

Application filed January 12, 1918. Serial No. 211,526.

To all whom it may concern:

Be it known that we, FRED A. PUTNAM and PERCY I. ALEXANDER, citizens of the United States, and residents of Melrose, county of Middlesex, State of Massachusetts, have invented an Improvement in Marking-Machines, of which the following description, in connection with the accompanying drawing, is a specification, like characters on the drawing representing like parts.

This invention relates to marking machines of the type illustrated in United States Patent No. 1,131,865, dated March 16, 1915. The device shown in said patent comprises a work support or platen on which the work to be marked is supported, a printing head having a plurality of independently-adjustable rotary type wheels, each provided on its periphery with a plurality of printing characters, means for adjusting the type wheels independently to bring any printing character thereon into printing position, and means to move the printing head toward and from the work support to perform the printing operation.

The machine illustrated in said patent also includes a type plate having fixed printing characters thereon, which type plate is supported by the printing head and is adapted to be held thereon in such position that when the printing head makes its printing movement the printed impression that is produced will be formed partly from the type wheels and partly from the type plate. The type wheels are each provided with a plurality of type-bearing projections on which the type characters are formed, and the type plate is arranged with a central opening through which the type-bearing

projections of the type wheels that are in printing position are adapted to project so that the portion of the type plate having the type characters thereon occupies the space between adjacent projections. When the type plate is thus in printing position it interlocks with the projections on the type wheels and prevents them from being adjusted. In order to adjust the type wheels the type plate is moved away from the printing head sufficiently to carry it out of engagement with said type wheels. Printing machines of this character are usually constructed so that when they are stopped they will be brought to rest with

the printing head raised, and the machine illustrated in said patent is provided with mechanism so that each time that the head is raised the type plate is moved away from the printing head and out of interlocking engagement with the type wheels so that whenever the machine is brought to rest, the type wheels are free to be adjusted.

In the present invention we have improved the construction illustrated in said patent by providing means which act normally to hold the type plate in its operative position so long as the machine is running, but which becomes operative to remove the type plate from interlocking engagement with the type wheels only when the machine is brought to rest. We accomplish this by providing mechanism actuated by the controlling means for the machine, which mechanism is operative only when the controlling means is actuated to bring the machine to rest and which when operative moves the type plate out of its interlocking engagement with the type wheels.

In order to give an understanding of our invention, we have illustrated in the drawing a selected embodiment thereof which will now be described, after which the novel features will be pointed out in the appended claims.

In the drawings, Figure 1 is a side view of a marking machine embodying our invention and showing the parts in the position they assume when the machine is at rest;

Fig. 2 is a side view of the printing head and type plate showing the parts in the position they assume when the machine is running;

Fig. 3 is a detail view of the controlling mechanism for the machine;

Fig. 4 is a view of the type plate.

The machine herein shown comprises a frame or base 1 having an arm 3 pivotally mounted thereon at 2, said arm carrying at its end a printing head 4 which includes a plurality of adjustable type wheels 5. Each type wheel is shown as having a plurality of type-bearing projections 6 having type or characters 7 formed on their faces. Any suitable means may be employed for adjusting the individual type wheels to bring any character into printing position, and

the device herein shown is similar to that illustrated in said patent and comprises a setting wheel 8 which is slidably mounted on a shaft 9 and which can be moved longitudinally of the shaft thereby to be brought into mesh with the projections 6 on any type wheel. After the setting wheel 8 has been brought into mesh with any type wheel, the latter may be turned by rotating the setting wheel by means of the hand-wheel 10. 11 indicates a work support or platen on which the work to be printed or marked is placed.

The arm 3 is vibrated to move the printing head toward and from the platen 11 by means of a cam 12 carried by a shaft 13, said cam acting against a roll 14 carried by the extension 15 of the arm 3, a spring 16 being employed to hold the roll or follower 14 in contact with the cam. The shaft 13 has a gear 17 thereon which meshes with and is driven by a pinion 18 fast on a driving shaft 19. The gear 17 is loose on the shaft 13 and is adapted to be clutched thereto by a suitable clutch, that herein shown comprising a clutch member 20 rigid with the gear 17 and a spring-pressed clutch dog 21 which is carried by an arm 22 that is fast to the shaft 13 and is acted upon by a suitable spring 23 which tends to carry it into clutching engagement with the clutch member 20. The clutch dog is controlled by a clutch-actuating lever 24 pivoted to the frame at 25 and having a toe portion 26 which is adapted to engage the tail 27 of the clutch dog when the lever is in the position shown in Fig. 3, thereby holding the clutch dog out of engagement with the clutch member 20. When the lever 24 is turned to depress the right-hand end thereof in Fig. 3, the clutch dog will be automatically thrown into clutching engagement with the clutch member 20 and the machine will continue in operation thereby clutching the shaft 13 to the gear 17 and the machine will continue in operation until the lever 24 is restored to the position shown in Fig. 3 when the end 27 of the clutch dog will engage the toe 26 as the shaft 13 rotates thereby to disengage the clutch, this occurring just when the arm 3 is in its raised position.

The lever 24 may be controlled by any suitable means. In the construction herein shown the work support or platen 11 is mounted in the frame 1 for vertical movement, said platen being connected by a rod 28 to a treadle 29 pivoted at 30 and one end 31 of the lever 24 is carried underneath the platen 11 so that when the platen is in its lowered position the controlling lever 24 will be thrown into its operative position thereby to hold the clutch disengaged, while when the platen is raised the lever will be carried into its inoperative position by the

spring 32, thus permitting the clutch to be engaged. Normally and when the machine is at rest, the platen is in its lowered position. To start the machine the operator depresses the front end of the treadle 30, thus raising the platen or work support and releasing the lever 24 with the result that the clutch will be automatically engaged. The machine will continue in operation until the treadle is released and the work support is lowered.

The type plate which is associated with the printing head is shown at 33 and it may have any desired type characters formed thereon. It is sustained by arms 34 pivoted to the printing head at 35, said arms being acted upon by a suitable spring 30 which tends to hold the type plate in its operative position shown in Fig. 2, in which position the projections 6 of the type wheels that are in printing position project through the opening 34 formed in the type plate so that the characters on the type plate are in the same plane as the characters on said projections 6.

By our invention we have provided means which is controlled by the clutch-controlling mechanism and which is operative when the clutch is released to move the type plate 33 out of interlocking engagement with the type wheels when the machine is at rest, as shown in Fig. 1, so that the type wheels are free to be adjusted, but which is inoperative to control the movement of the type plate so long as the machine is running whereby the type plate will be held in its operative position shown in Fig. 2.

The device we have herein illustrated for this purpose comprises a lever member 36 pivoted to the printing head at 37 and having an arm 38 that is adapted to engage an extension 39 of the arm 34. The lever member 36 is also provided with another arm 40 which is adapted to cooperate with an arm 41 fast on a rock-shaft 42, the latter having an arm 43 fast thereon which extends forwardly and the front end of which underlies the work support 11. The arm 41 is acted upon by a spring 44 which tends to draw it rearwardly into its inoperative position when the work support 11 is raised.

The construction and shape of the abovementioned parts are such that when the work support 11 is in its lowered position shown in Fig. 1, the engagement of the work support with the arm 43 will throw the arm 41 into its operative position shown in Fig. 1. When in this position it will be engaged by the arm 40 of the lever 36 as the printing head is raised thereby turning said lever 36 and causing the arm 38 thereof to act on the projection 39 and turn the arms 34 in a direction to carry the type plate 33 out of interlocking engagement with the type wheels.

When the work support 11 is in its ele-

vated position, which is the position it assumes while the machine is running, the spring 44 will hold the arm 41 in its inoperative position shown in Fig. 2, in which 5 position it is out of the path in which the end of the arm 40 travels as the printing head is raised and lowered during the printing operations so that the spring 50 is free to hold the type plate in its operative position 10 shown in Fig. 2. The type plate will thus be held in such position so long as the machine is running, but as soon as the work support 11 is lowered into the position shown in Fig. 1 thereby to throw the clutch out of 15 operation the arm 41 will be carried into its operative position in which it will engage the arm 40 of the lever 36 as the printing head is raised thereby to swing the type plate out of operative position. Hence so 20 long as the machine is running the type plate will be in its operative position, but as soon as the machine comes to rest, the type plate will be thrown out of interlocking engagement with the type wheels thereby to 25 permit the latter to be adjusted.

We claim:

1. In a marking machine, the combination 30 with a work support, of a printing head movable toward and from the work support and having a plurality of adjustable type wheels, a type plate carried by the printing head and movable relative thereto into and out of interlocking engagement with the type wheels, controlling means by which the 35 actuating mechanism is rendered operative or inoperative, and means operated by said controlling means to move the type plate

out of interlocking engagement with the type wheels when the controlling mechanism is actuated to bring the machine to rest. 40

2. In a marking machine, the combination with a frame, of a work support carried thereby and capable of vertical movement, a printing head movable toward and from the work support and having a plurality of 45 adjustable type wheels, a type plate carried by the printing head and movable thereon into and out of interlocking engagement with the type wheels, actuating mechanism for the printing head, a clutch therefor controlled by the vertical movement of the work support, and means also controlled by said work support for moving the type plate out of interlocking engagement with the type wheels when the work support is in position 50 to bring the machine to rest. 55

3. In a marking machine, the combination with a frame, of a vertically-moving printing head mounted thereon and having a plurality of adjustable type wheels, a type plate 60 pivotally carried on said head and movable into and out of interlocking engagement with the type wheels, a vertically-movable platen carried by the frame, a lever pivoted to the frame and controlled as to its position by 65 the position of the platen, and means actuated by said lever when the platen is lowered to cause the type plate to move out of interlocking engagement with the type wheels when the type head is raised. 70

In testimony whereof, we have signed our names to this specification.

FRED A. PUTNAM.
PERCY I. AXFORD.
